UNITED STATES PATENT OFFICE.

BENJAMIN F. MIKESELL AND HARRY FOX GILLIAM, OF KANSAS CITY, MISSOURI.

PHOTOPRINTING APPARATUS.

Application filed May 23, 1921. Serial No. 471,889.

To all whom it may concern:

Be it known that we, BENJAMIN F. MIKESELL and HARRY F. GILLIAM, citizens of the United States, and residents of Kansas

5 City, county of Jackson, State of Missouri, have invented a certain new and useful Improvement in Photoprinting Apparatus, of which the following is a complete specification.

10 This invention relates to photo-printing apparatus and has for its object to produce means whereby the printing opening may be varied in extent in order to accommodate prints of different dimensions.

15 Another object is to produce means for reliably holding in position the print so that the downward swing of the cover member shall not disturb the position of the print with regard to the underlying negative.

20 A still further object is to produce a device possessing certain novel and useful features of construction and organization of parts as hereinafter described and claimed; and in order that it may be fully 25 understood, reference is to be had to the accompanying drawing, in which:

Figure 1 is a top plan view of the device partly broken away to more clearly illustrate parts otherwise hidden.

30 Figure 2 is a section on the line II—II of Figure 1.

Figure 3 is a detail of a part of the print holding member.

35 In the said drawing, where like reference characters identify corresponding parts, 1 is a printing table of ordinary form and construction and provided with the customary printing panel or central opening in which is fitted a glass negative-supporting plate 2, and secured to said table at any suitable points are a pair of brackets 3 in the upper ends of which are pivoted arms 4 bearing at their outer ends the swinging cover member 5, the movement of said cover 45 member being controlled by any suitable source of power, (not shown).

50 6 and 7 respectively indicate transversely and longitudinally extending pairs of masks, resting on and having sliding engagement with the table 1, the masks of each pair being adapted to move toward and away from each other as will hereinafter appear. The pair of masks 7 overlie and rest on the masks 6. Secured to one corner of each of the masks 7 and extending downwardly through slots 8 in the surface of the

table, are operating arms 9, and secured to masks 6 and extending downwardly through slots 10 in the table near the front margin thereof are operating arms 11.

60 The operating arms of the two pairs of masks, respectively, engage right and left handed threaded portions of the shafts 12 and 15, in order that rotation of the shafts shall cause the masks of each pair to move forward or away from each other, said shafts being journaled in brackets 13 and 16 depending from the underside of the table as will be readily understood.

65 The shaft 12 is fitted at its outer end with an operating crank 14, which will project forward of the front edge of the table in a convenient position for use, it being understood that its rotation will cause the relative approaching or receding movements of 70 the masks 7, thus regulating the width of the exposed area of the glass plate 2 for printing purposes. Shaft 15 is equipped at one end with a gear wheel 17 which meshes with a gear wheel 18 journaled in a downwardly depending bracket 19, and adapted for rotation by a crank handle 20. Rotation 75 of said handle effects opening or closing movement of the masks 6, and thus the length of the exposure opening for printing purposes may be conveniently regulated.

80 One of each of the masks may be provided at a corner with an indicating finger 21, which will point to a series of indicia 22 on the surface of the table. These indicia 85 may be of any suitable character to indicate the dimensions of the printing space of the panel exposed for use.

85 It has been found desirable to provide some sort of clamping means for holding the print paper in position just as the cover member attains its horizontal position, and for this purpose we have provided the rear mask 7 with a series of ears 23 between 90 which are pivoted the rear end of a series of forwardly extending fingers 24 with their front ends connected by a clamping jaw 25, adapted to clamp down and hold the print paper by contacting with one margin of the same, as will hereinafter appear. It will 95 be apparent that the cover plate 5 will in its downward movement come into contact with the arms 24 and press the clamping member 25 down upon the print paper. In order 100 that said clamping member may be immediately withdrawn from position when the cover member moves upwardly each arm 24

2
is engaged by a sliding collar 26, and secured to each collar is a spring 27 tending to raise the clamping jaw from contact with the print paper, the other end of said springs being engaged and held in position in lugs 28 projecting upwardly from the surface of the table, as illustrated. It will be evident that this sliding arrangement is provided, in order that the springs may 10 maintain a lifting action on the clamping jaw, disregarding the position of the clamping jaw due to movements of the mask which carries said jaw carrying frame, as will be readily understood, and that said 15 jaw will therefore always be in position to clamp down on the margin of a print, regardless of the width thereof.

In order to aid in placing a print P in position over the negative N, the rear mask 20 7 is provided with an upwardly extending rib or shoulder 29 against which one edge of the print is adapted to abut, and one member of the pair of masks 6 is provided with a shoulder or rib 30 against which another edge of the print is adapted to abut, as will be readily understood, it being apparent that if a print is placed in abutting relation with the lugs it will be in the correct printing position over the negative. 25

30 From the above description, it will be apparent that we have produced a device of the character described, which possesses all of the features of advantage set forth as desirable, and while we have described and 35 claimed the preferred embodiment of the same, we reserve the right to make all changes properly falling within the spirit and scope of the appended claims.

We claim:

40 1. In a photo-printing device, the combination of a table, a negative supporting panel in said table, a mask movable across said panel, and a clamping jaw pivoted to said mask.

45 2. In a photo-printing device, the combination of a table, a negative supporting panel in said table, a cover member adapted to cover said panel, a mask movable across said panel, and a clamping jaw pivoted to said mask.

50 3. In a photo-printing device, the combination of a table, a negative supporting panel in said table, a cover member adapted to cover said panel, a mask movable across said panel, and a clamping jaw pivoted to said mask and adapted to be actuated by said cover member to clamp the print paper between said jaw and panel.

55 4. In a photo-printing device, the combination of a table, a negative supporting panel in said table, a cover member adapted to cover said panel, a mask movable across said panel, a clamping jaw pivoted to said mask and adapted to be actuated by said cover member, and yielding means for auto-

matically returning said clamp to normal position after actuation by said cover member.

5. In a photo-print device, the combination of a table, a negative supporting panel 70 in said table, a cover member adapted to cover said panel, a pair of masks resting on and movable toward and away from each other and transversely of the table across said panel, a clamping jaw pivoted on one 75 of said pair of masks, and a pair of masks resting on and movable toward and away from each other and longitudinally of said table across said panel.

6. In a photo-printing device, the combination of a table, a negative supporting panel in said table, a pair of masks adapted 80 for movement longitudinally of said table across said panel, means for simultaneously moving said masks away or toward each other, a second pair of masks adapted for movement transversely of said table across 85 said panel, means for simultaneously moving said second pair of masks away from or toward each other, a shoulder on one of said first-named pair of masks, and a second shoulder disposed at right angles to said first-named shoulder and carried by one of said second pair of masks, said shoulders 90 co-operating to form a guide for the placing of 95 a print.

7. In a photo-printing device, the combination of a table, a negative supporting panel in said table, a pair of masks adapted 100 for movement longitudinally of said table across said panel, means for simultaneously moving said masks away from or toward each other, a second pair of masks adapted for movement transversely of said table across said panel, a clamping jaw pivoted to 105 one of said second pair of masks, and means for simultaneously moving said second pair of masks away from or toward each other.

8. In a photo-print device, the combination of a table, a negative supporting panel in said table, a cover member adapted to cover said panel, a pair of masks resting on and movable toward and from each other and transversely of said table, a shoulder on one of said transversely movable masks 110 adapted to act as an abutment for a print, a pair of masks resting on and movable toward and from each other and longitudinally of said table, and a shoulder on one of said longitudinally movable masks adapted 115 to act as an abutment for a print and at right angles to said first-named shoulder.

9. In a photo-printing device, the combination of a table, a cover member adapted to cover said panel, a pair of masks resting on and movable toward and from each other and transversely of said table, a shoulder on one of said transversely movable masks 120 adapted to act as an abutment for a print, a clamping jaw adapted to clamp down upon 125

the print forward of said shoulder, a pair of masks resting on and movable toward and from each other and longitudinally of the table, and a shoulder on one of said longitudinally

5 movable masks adapted to act as an abutment for the print and at a right-angle to said first-named shoulder.

10. In a photo-print device, the combination of a table, a negative supporting panel in said table, a cover member adapted to cover said panel, a mask adapted for movement across said table, a clamping jaw pivoted to said mask and adapted for actuation in one direction by said cover member, 15 and resilient means for returning said jaw to normal position.

11. In a photo-print device, the combination of a table, a negative supporting panel in said table, a cover member adapted to cover said panel, a mask adapted for movement across said table, a clamping jaw pivoted to said mask and adapted for actuation in one direction by said cover member, and resilient means secured to the table and having sliding engagement with the clamping jaw for returning the latter to normal position. 20 25

In witness whereof we hereunto affix our signatures.

HARRY FOX GILLIAM.
BENJAMIN F. MIKESELL.
